DEVICE FOR ATTACHING LABELS ON
BOTTLES, CANS AND THE LIKE

Georg Viktor Wrangle, Alsten, Sweden

Application December 24, 1935, Serial No. 56,101
In Sweden August 17, 1934

8 Claims. (Cl. 216—54)

The present invention relates to a device for attaching labels on bottles, cans or the like carried forward by a conveyor. The object of the invention is to develop such a device of a simple and cheap construction working without danger of damaging the bottles and by means of which it will also be possible to attach the label at such places, for example the bottle neck, where owing to difficulties of reaching those places by means of a machine—it was necessary to attach the labels by hand.

The device according to the invention is in the first place characterized thereby that it consists of one or several rotatable, elastic members, arranged laterally to the conveyor and adapted while deforming to be pressed against a bottle during a part of the rotation, when said bottle is passing the member, one or several conduits or channels opening on the surface of the respective elastic member being arranged to be connected or disconnected with a source of vacuum in such a way that, when their openings pass a pile of labels or the like, they are brought into connection with the source of vacuum, thereby grasping and carrying along a label, but after continued rotation of the elastic member into engagement with the bottle they are brought into connection with the air thereby releasing the label and allowing it to be pressed against the bottle by the deformation of the elastic member and attached to the bottle.

The device may either consist of a single elastic member as described—which is then rotatable around its own longitudinal axis—or of a number of elastic members distributed around a common axis of rotation, which members are stationary in relation to their own longitudinal axis.

The elastic member or members suitably consist of a hollow body of for instance rubber which is kept expanded by means of compressed air.

Fig. 1 is a diagrammatical plan view of an embodiment of the device according to the invention cooperating with a conveyor for the bottles.

Fig. 2 shows, on a greater scale, a vertical section through the device, and Fig. 3, partly in section, a plan view of the device.

Fig. 4 is a diagrammatical plan view of a modified embodiment of the device.

In Fig. 1, 1 is a conveyor web by means of which the bottles 2 are brought into the sections of a rotating feed table 3 of a known kind. 4 is a pile of labels, and 5 the label attaching device according to the invention. The labelled

bottles are carried away by means of a conveyor web 6.

The device of attaching labels illustrated in detail in Figs. 2 and 3 consists of a rotating shell or hollow cylinder 7 of elastic material, such as rubber or the like that is expanded by means of internally admitted compressed air. The shell 7 is attached to the vertical driving shaft 8 and is attached at the top between the nuts 9 and 10 and at the bottom between the washer 11 and the plate 12, which participate in the rotation of the axis 8. The shell is so positioned in relation to the feed table 3 that the circumference of the shell is pressed against the bottle and deformed at the place of contact. 13, 13' are vacuum conduits, suitably of rubber or similar resilient material. On the drawing, two conduits 13, 13' are disclosed, but there may, of course, be any suitable number of them. The conduits 13, 13' are at the top divided into a number of branch conduits 14, 14' curved towards the surface of the shell and opening at different points on the same. In the illustrated embodiment each conduit 13, 13' is divided in four branch conduits, but there may be any other suitable number of them.

The ends of the branch conduits 14, 14' are suitably connected to the shell 7 by means of fusing. The lower ends of the conduits 13, 13' pass corresponding holes in the washer 11 and the shell 7, and are inserted into and secured in a suitable way in holes 15 in the plate 12.

The shell 7 with the plate 12 is mounted upon a stationary plate 16 in which two concentric, arc-shaped grooves 18 and 19, separated by a relatively short interspace 17, are made. The longer groove 18 is in constant communication with a vacuum source by means of a conduit 23, while the shorter groove 19 constantly communicates with the outer air.

The shell is maintained expanded by means of compressed air that for instance may be conveyed from a source of compressed air by a channel 20 bored in the shaft 8 and a valve 22, for instance a rubber valve of the kind generally used in bicycles attached at the opening 21 of said channel in the surface of the shaft, which valve automatically admits air to the shell when the difference in pressure owing to leakage has reached a certain value.

The device works in the following manner.

When the shell is rotating in the direction indicated by the arrow and reaches the position indicated in Fig. 3, the opening of the vacuum conduit 13' should be above one end of the groove

18. Vacuum is now formed in the conduit 13' and the branch conduits 14' so that the foremost label in the pile will be sucked towards the shell 7, as indicated in Fig. 3. At the continued 5 rotation of the shell, the label is brought along and held by the vacuum, because the conduit 13' communicates with the groove 18. When passing the space 17, the communication with the groove 18 and the vacuum source is interrupted. 10 Yet, a sufficient partial vacuum is maintained in the conduits 13 and 14 as to hold the label. During the continued rotation of the shell, the label is brought between the bottle and the shell and is thus pressed against the bottle while the 15 shell is being deformed. Owing to the deformation, the label is pressed uniformly against the bottle. When the label has arrived to the right position in relation to the bottle, the conduit 13 should be above one end of the groove 19 that 20 communicates with the outer air so that the vacuum in the conduits 13, 14 will be interrupted and the label released.

The labels in the pile 4 may be previously gummed so as to be directly fastened to the wet 25 bottles without further means. A pasting device, for instance a rotating pasting brush, may instead be arranged laterally to the shell in such a way that the label, held by the shell, will be coated with paste, when it is passed in front 30 of it.

By means of the device according to the invention, the labels may be applied to such places where labels hitherto could not be attached by machinery, for instance at the bottle neck, as 35 indicated at 24 in Fig. 2. For this purpose, the shell may be extended upwards in relation to the bottle or be provided with a more expanded upper part which is deformed when engaging the bottle neck. The upper part of the shell may then 40 operate with a separate pile of labels and separate vacuum conduits or conduits branched off from other vacuum conduits may then open on said level in the surface of the shell.

In the embodiment illustrated in Fig. 4 a number of similar elastic members 25 are distributed around a common shaft of rotation 26, whereas the members 25 are stationary in relation to their own longitudinal axis. They are mounted upon a rotating plate or table 27 in which openings corresponding to the openings 15 in Fig. 2 for the vacuum conduits of each elastic member are provided. Below the plate 27 a stationary plate, corresponding to the plate 16 in Fig. 2 will be arranged, in which grooves communicating 55 respectively with a vacuum source and the outer air are provided.

The invention is not limited to the above described embodiments, but different details may be modified in different ways without departing 60 from the idea of the invention.

Thus the elastic member or members may consist of a cover of some suitable elastic or non-elastic material, such as rubber, fabric or the like that is expanded otherwise than by means of compressed air. The material may, for instance, be expanded by members that are arranged inside the cover and adapted to yield resiliently, such as elastic ribs or the like, when the cover is 65 being deformed.

The cross-section of the expanded elastic member need not necessarily be circular as shown but may be of many different shapes, for instance oval or another rounded shape or unround 70 shape, for instance lanceolate, triangular, quad-

rangular, or polyangular shape with a plane or curved lateral surfaces.

The bottles or the like that are to be labelled need not be conveyed on a rotating feed table to the labelling place, as shown, but this can be effected by means of any suitable feeding or conveying device. Of whatever kind the used feeding or conveying device may be, the driving devices for the said feeding device and those for the elastic member or members should, however, be 10 mutually so adapted that the latter will be rotated about their axis of rotation in synchronism with the feed motion of the bottles or the like so that a bottle always at the right moment will arrive to the labelling place at the same time as 15 an elastic member arrives there or respectively turns its side holding the label towards the labelling place and that the bottle and the elastic member also during the transmittance of the label to the bottle move synchronously to avoid 20 a crinkling or folding of the label.

Instead of a pile of labels of the kind indicated on the drawing, a rotating label transmitter may be used which transmits labels to the required places on the elastic member or members synchronously with the motion of the latter.

Having now particularly described the nature of my invention and the manner of its operation what I claim is:

1. Device for labelling bottles, cans and the like, comprising a conveyor for the bottles, a number of elastic labelling members, means for rotating said labelling members about an axis, mounting means for said labelling members so adapted in relation to said conveyor that the rotating labelling members are pressed against passing bottles on the conveyor being resiliently deformed thereby, a number of air conduits arranged inside of said labelling members and opening on a part of the outer surface of the labelling members adapted to be pressed against the bottles, means for holding a pile of labels close to the path of the outer surface of the rotating labelling members, means for connecting a source of vacuum to said air conduits when openings of the latter arrive in front of the pile of labels so that a label will be seized and carried along by the rotating labelling member while a vacuum is maintained in said air conduits, and means for interrupting said connection to the source of vacuum and for connecting said air conduits to the outer air when the labelling member is resiliently pressed against the bottle thus releasing the label from the labelling member.

2. Device for labelling bottles, cans and the like, comprising a conveyor for the bottles, a single elastic labelling member, means for rotating said labelling member about its own longitudinal axis, mounting means for said labelling member so adapted in relation to said conveyor that the rotating labelling member is pressed against passing bottles on the conveyor being resiliently deformed thereby, a number of air conduits arranged inside of said labelling member and opening on a part of the outer surface of the labelling member adapted to be pressed against the bottles, means for holding a pile of labels close to the path of the outer surface of the rotating labelling member, means for connecting a source of vacuum to said air conduits when the openings of the latter arrive in front of the pile of labels so that a label will be seized and carried along by the rotating labelling member while a vacuum is maintained in said air conduits, and means for interrupting said connection to the

- source of vacuum and for connecting said air conduits to the outer air when the labelling member is resiliently pressed against the bottle thus releasing the label from the labelling member.
- 5 3. Labelling device according to claim 1, and wherein each labelling member consists of a hollow body of elastic material that is kept expanded by means of compressed air.
4. Labelling device according to claim 1, and 10 wherein a plurality of elastic labelling members are grouped about a common axis of rotation, each labelling member being stationary in relation to its own longitudinal axis.
5. Labelling device according to claim 1, and 15 wherein each labelling member consists of a hollow elastically expanded body, a number of flexible vacuum conduits arranged inside of said hollow body being attached with their openings, at one end in the surface of the hollow body and 20 at the other end in ports arranged in a member attached to the driving shaft of the labelling member, which ports are adapted to be alternatively connected to the source of vacuum or the outer air during the rotation of the labelling member.
- 25 6. A labelling device according to claim 1, and wherein each air conduit is branched off in a number of branch conduits opening at different points on the surface of the labelling member to form points of seizure for the labels.
7. Labelling device according to claim 1, and 5 wherein each labelling member consists of a hollow elastically expanded body, a number of flexible vacuum conduits arranged inside of said hollow body being attached with their openings at one end in the surface of the hollow body and 10 at the other end in ports arranged in a plate attached to the driving shaft of the labelling member and abutting against a stationary plate provided with two openings, of which one is connected to the source of vacuum and the other to 15 the outer air, said ports being adapted to alternatingly register with said openings during the rotation of the labelling member.
8. A labelling device according to claim 2, and 20 wherein a longitudinal bore in the driving shaft of the labelling member is connected to a source of compressed air and opens into the interior of the labelling member by means of an automatic pressure valve.
